SUCTION CLEANER

Carl O. Penn, Canton, Ohio, assignor to The Hoover Company, North Canton, Ohio, a corporation of Ohio

Application November 11, 1943, Serial No. 509,875

9 Claims. (Cl. 183—57)

1

The present invention relates to suction cleaners in general and more particularly to a new and novel suction cleaner in which a fixed filter within the machine must be cleaned before the machine can be opened to empty the collected foreign matter. More specifically the invention comprises a suction cleaner with a permanently embodied filter and a removable dirt container, access to the dirt container being controlled by program release means.

It is an object of the present invention to provide a new and improved suction cleaner. It is a further object of the invention to provide a new and improved suction cleaner embodying program release means for the dirt-retaining means. A still further object of the invention is to provide a suction cleaner incorporating an initial dirt separator, suction-creating means, a final dirt separator, means to remove the collected foreign material from the final dirt separator and to transport it to the initial dirt separator, and program-controlled release means which require that the final dirt separator be cleaned before foreign material can be removed from the initial dirt separator. Still another object of the invention is to provide a suction cleaner in which a predetermined program must be followed, including the cleaning of a final filter, before the cleaner can be opened and the dirt emptied therefrom. Still another object of the invention is to provide a new and novel cover release mechanism for a suction cleaner. A still further object of the invention is to provide a suction cleaner in which a filter-cleaning nozzle must be reciprocated a predetermined number of times relative to the filter to remove the collected foreign material therefrom before the machine can be opened and the collected foreign material removed. These and more specific objects will appear upon reading the following specification and claims and upon considering in connection therewith the attached drawings to which they relate.

Referring now to the drawings in which a preferred embodiment of the invention is illustrated and in which the same reference character refers to the same parts of the various views:

Figure 1 is a vertical longitudinal section through a cleaner embodying the present invention;

Figure 2 is a partial end view of the cleaner illustrated in Figure 1 with a part of the cleaner cover broken away;

Figure 3 is a section through the air-controlling valve means, being taken upon the line 3—3 of Figure 1;

2

Figure 4 is a partial section upon the line 4—4 of Figure 1;

Figure 5 is a partial section upon the line 5—5 of Figure 1 and shows the means which retain the actuating handle in its operative and inoperative positions;

Figure 6 is an enlarged view of the program release mechanism illustrated in Figure 1, the parts being shown positioned so as to permit the removal of the casing cover;

Figure 7 is a section upon the line 7—7 of Figure 6.

In the common canister suction cleaner foreign material is collected within a removable dust bag. When this bag has become filled with foreign material to an extent such that the back pressure opposing the flow of cleaning air through the machine is excessive the machine is opened, the bag removed and cleaned as by shaking. The bag-cleaning operation is objectionable in that foreign material enters the air and is noticeable to the user. In an improved type of suction cleaner a removable receptacle within which foreign material collects is provided and, being made of metal or similar material from which foreign material readily separates, permits of cleaning in a much less undesirable operation. If the machine of this latter type embodies a filter which is permanent within the cleaner, in the sense that it is not removed with the removal of the foreign material, then the filter must be cleaned at intervals to prevent the building up of an undesirable back pressure.

In a suction cleaner constructed in accordance with the preferred embodiment of the present invention the fixed final filter within the machine is provided with cleaning means which remove the collected foreign material from it and transport that material to a readily emptied removable dirt receptacle. To insure that the final filter will be cleaned and that the receptacle will not be emptied by the operator without periodically cleaning the filter, there is provided a program release mechanism which places the operator under the necessity of cleaning the final filter before he can remove the receptacle to empty the dirt.

Referring now particularly to the drawings a horizontal canister type machine is illustrated in Figure 1 in vertical longitudinal section. The cleaner is seen to comprise an elongated casing 1 which may be cylindrical and which is slidably supported by longitudinally extending runners 2 in a common and well known manner. One end 55 of cylindrical casing 1 is closed by a fixed cover

plate 3 which is provided with an exhaust port 4 of a type adapted to receive and seat the cleaner end of the usual and well known dusting tools. The opposite end of the cleaner is closed by a removable cover plate 6 embodying an intake port 7 also of a type adapted to receive and seat dusting tools. Cover 6 is sealed to casing 1 in air-tight relationship by an intermediate seal element 5. The bottom of the removable cover 6 is removably held in place by a spring plate support 8 which supports the cover and tends to force it toward the casing end ring 9 fixed on the casing 1. The upper end of cover 6 is removably latched to the casing 1 by means which will be fully described and which include program release means the operation of which requires that the operator clean the cleaner filter before the cover can be removed.

Within casing 1 are positioned a front transverse plate 11 and a rear transverse plate 12, the latter being provided with a plurality of ports 13 around its periphery and immediately inside the casing 1. Plates 11 and 12 support the suction-creating unit of the cleaner comprising a motor 14 and a multiple fan unit 16. The casings of fan unit 16 and motor 14 are fixedly secured to the plates 11 and 12 and the motor shaft 17 extends completely through the casing of fan unit 16, where it carries a plurality of fans 18, through the front plate 11, and into the chamber 19 where it carries the rotary separator 21. Rotary separator 21 is of a well known type which, when rotating at high speeds permits air to pass through it while rejecting and throwing radially outwardly foreign material of appreciable mass which attempts to enter. A plurality of minor air-moving blades 22 are formed upon separator 21 adjacent the plate 11 which serve to prevent air from passing from the chamber 19 inwardly toward the motor shaft without passing through the apertures of the separator 21. The suction-creating fans 18 cause air to pass through the separator 21, through the eye 23 of the fan chamber unit, through the fan unit, and to be exhausted through the exhaust ports 24. The space around the motor 14 and fan unit 16 into which the air is exhausted is indicated by the reference character 26 and is called the final filter chamber, deriving its name from the fact that it is enclosed by an air permeable filter 27 extending between plates 11 and 12. The space outside of the filter 27, and within the casing 1, is indicated by the reference character 28 and may be referred to as the discharge chamber, being connected through the port 13 in the rear wall 12 to the discharge port 4. Foreign material entering the cleaner will be nearly all removed within the initial separator chamber 19 by the action of the centrifugal separator 21 and will collect within the removable dirt container 20. A small part, however, of the foreign material, particularly material of very slight mass, may pass through the separator and into the fan unit to be exhausted into the final dirt separator 26 to be collected upon the interior surface of the filter 27. The air less the foreign material passes through the filter of the discharge chamber and escapes through the discharge port 4. As the interior surface of the filter 27 is not readily accessible to the operator means are provided to clean it comprising a filter-cleaning nozzle 31, ring like in form and provided with a surface-contacting mouth. Nozzle 31 is interiorly connected by a rigid conduit 32 to the interior of the initial dirt separator chamber 19, the conduit 32 being slidably mounted in the

wall 11 by the air seal mounting 33. The nozzle is adapted to slide over and contact the entire length of the filter 27 being movable between resilient bumpers 34 carried by the plates 11 and 12.

Conduit 32, forwardly of the plate 11, is closed by a fixed closure plug 36 and is provided rearwardly of the plug with a side valve port 37. To actuate the conduit 32 and the filter-cleaning nozzle 31, and also to close the valve port 37 when it is not desired to use the nozzle, there is provided an exterior operating handle 38 and a tube 39. The latter extends through the cover 6 at a slot port 41 formed therein to accommodate it, is slidably carried in a depending guide 42 formed integrally in the end ring 9 of the casing 1 and seats rotatably on the end portion of conduit 32.

Tube 39 at its inner end is formed with a side port 43 adjacent the port 37 in the conduit 32. In the normal position of the handle during cleaner operation, as shown in full lines in Figures 1 and 3, the ports are 180 degrees out of alignment. When the handle is rotated through 180 degrees port 43 moves into alignment with port 37 and the interior of tube 32, and so the nozzle 31, is connected to the separating chamber 19. To permit of relative rotation of tube 39 relative to conduit 32 and at the same time to prevent longitudinal separation thereof, the tube 39 and the conduit 32 are provided with mutually engaging circumferential grooves, illustrated and indicated at 44, adjacent the plug 36.

In the normal operation of the machine it is desirable that the handle 38 and the filter-cleaning nozzle 31 be held in a definite position. A bracket 45 on the inside of the casing 1 is positioned forwardly of a stop lug 47 upon the tube 39 in all angular positions of the tube except the nozzle-operating position illustrated in dotted lines in Figures 1 and 2. Unless the handle is turned to the dotted line position the bracket prevents forward movement of the tube and nozzle through obstructing the lug 47. It is also desirable that the handle be held either in its normal angular position or that it be held in its nozzle-operating angular position. To accomplish this there is provided within the conduit 32 a spring-pressed detent 48 which extends outwardly through the conduit in a suitable sealed relationship. The extreme end of the tube 39 surrounding conduit 32 is formed with two spaced detent-receiving seats or pockets 49 into which detent 48 is adapted to slide by slightly compressing its spring and from which it can be displaceable by a slight rotational force upon the handle. Actually, of course, the seats 49 upon the tube 39 rotate relative to the detent for it is the tube 39 carrying the seats which is rotatable.

In the normal operation of the cleaner air passes from the final filter chamber 26 outwardly through the filter 27 into the discharge chamber 28, the foreign material collecting upon the interior surface of the filter. In the filter-cleaning operation the nozzle 31 is reciprocated back and forth over the surface of filter 27 a plurality of times in order that the filter-cleaning air entering from the discharge chamber 28 and passing through the filter 27 into the nozzle 31 will have sufficient opportunity to remove the collected material. The number of times which the nozzle must be reciprocated can be determined empirically but is in the neighborhood of three or four. According to the present invention before the dirt container 20 can be removed the

filter 27 is to be cleaned and accordingly the cover plate 6, which must be removed to gain access to removable container 20, is normally locked to the casing 1 and can only be removed by the operator actuating a program release mechanism. This program release mechanism is directly connected to the actuating mechanism for the filter-cleaning nozzle and the filter-cleaning nozzle must be reciprocated the desired number of times before the cover can be removed. This mechanism will now be described.

Removable cover 6 carries an inwardly projecting arm 51, the slotted end of which extends in sealed relationship through an aperture formed in a housing 52 carried below the top of main casing 1. During normal cleaner operation arm 51, and so the cover 6 fixed thereto, is held against outward displacement by a hooked latch 53 pivotally mounted upon a bracket 54 within the housing 52. Latch 53 is held in both latching and non-latching positions by a spring 56 which connects to it and to the bracket 54, the connections being upon opposite sides of the pivotal mounting of the latch and the spring moving over center with respect thereto as the latch moves from one to the other position. The latch carries a pivoted "trip arm" 57 which is normally spring-pressed toward a fixed stop pin 58 on the bracket 54 but which is adapted to be pivoted into contact with a stop pin 59 carried by the latch 53 upon its opposite side.

A ratchet wheel 61 is rotatably mounted upon a shaft 62 carried by the bracket 54. An adjacent rocker arm 63 on shaft 62 carries a spring-pressed pawl 64 adapted to engage the teeth of ratchet wheel 61 and to rotate that element in a counterclockwise direction, as viewed in Figures 1 and 6. Rotation of the ratchet wheel in clockwise direction as viewed in those figures is prevented by a second spring-pressed pawl 66 pivoted on the bracket 54. The ratchet wheel 61 carries several axially projecting pins 67 which are adapted to contact the lower end of the trip arm 57 of the latch 53 with the latch in its holding position. Rotation of the ratchet wheel 61 in a counterclockwise direction, as viewed in Figure 1, effects the contact of a pin 67 with the trip arm 57 and the pivotal movement of that arm from the bracket-carried stop 58 into contact with the latch-carried stop 59. Further movement of the pin results in the pivotal movement of the latch until the spring 56 moves over center with respect to the latch pivotal axis at which time the latch snaps into its open position illustrated in Figure 6.

Rotation of the ratchet wheel 61 to effect the movement of the latch is accomplished by a headed pin 71 which slidably seats in seated relationship in the side wall of the housing 52 in position to be contacted by a shoulder 72 on conduit 39 near its forward end. As handle 38 is drawn outwardly, and near the end of the movement of the nozzle 31 toward the front of the machine, the shoulder 72 contacts the pin 71 and forces it inwardly in the housing 52. The forward end of the headed pin 71 contacts the outer end of the rocker arm 63 with each inward movement, resulting from each forward stroke of the nozzle 31. The rocker arm 63, through the engagement of the pawl 64 with the ratchet wheel, rotates that wheel in a counterclockwise direction. This rotation continues as the nozzle is reciprocated by the handle 31 until the following pin 67 engages the trip arm 57 to perform its latch actuating function described above. Obviously

the spacing of the pins 67 will determine the number of reciprocations of the nozzle 31 which must be provided in order to release the cover.

When the filter-cleaning nozzle is being used to clean the filter 27 it is desirable that all of the air passing through the suction-creating means of the cleaner perform the useful function of cleaning the filter. If the intake port 7 remains open certain air will enter therethrough and this air, which of course is also handled by the suction-creating means of the cleaner, will reduce to that extent the air which is drawn from the nozzle 31 through the conduit 32. Accordingly it is desirable that the intake port 7 be closed during the filter-cleaning operation and this is accomplished by providing a valve plate 81 pivotally mounted upon a pin 82 on the interior of the cover 6 and movable between port-closing and port-opening positions. A coil spring 83 between the head of pivot pin 82 and the valve 81 urges the valve toward the cover 6 so as to seal with the mouth of port 7. A second coil spring, indicated at 84, also encircles the pivotal axis 82 and exerts a pivoting force upon the valve 81 to move it into port-closing position.

A cross head 86 carries a pin 87 which engages a slotted upper end of the valve plate 81 being itself slidably mounted on the inner surface of cover 6. Cross head 86 extends in sealed relationship through its seat in cover 6 into abutting contact with the handle 38, as illustrated in Figure 2, when the handle is in inoperative or cleaner-operating position. When the handle is moved to its own operating or nozzle-actuating position, illustrated in dotted lines in the same figure, the cross head 86 is released and, under the actuation of the coil spring 84, the valve 81 moves into port-sealing position and the cross head moves transversely outwardly. It is adapted to be contacted and moved to its former position by the handle when the latter is again moved to its full line position illustrated in Figure 2.

The operation of the filter-cleaning mechanism and the removal of the dirt contained therein will now be explained. The machine having been used for a considerable period of time, and the operator being of the opinion that the dirt container 20 should be emptied, he pivots the handle 38 from the full line position to the dotted line position illustrated in Figures 1 and 2. Thereupon plate valve 81 moves into position to close the intake port 7 and all of the air which moves through under the actuation of the suction-creating means is circulated through the filter-cleaning nozzle 31. The rotation of the actuating handle 38 through 180 degrees moves the stop lug 47 into position so that it can move past the bracket 46 on the casing 1. This permits the handle to be pulled inwardly and outwardly relative to the front of the machine and, accordingly, the nozzle 31 to move longitudinally of the casing and over the surface of the filter 27. The handle is retained in its upper or nozzle-operating position, as it was retained in its lower initial position, by the cooperation of the spring-pressed detent 48 carried by the conduit 32 with a detent seat carried by the tube 39. The operator reciprocates the handle and the nozzle rearwardly and forwardly several times and with each movement tube-carried shoulder 72 abuts and forces inwardly the slide pin 71 resulting in the partial rotation of the ratchet wheel 61. The start of this operation found the latch 53 in its cover-retaining position, illustrated in Figure 1. The subsequent rotation of the ratchet wheel upon

the reciprocation of the nozzle causes the ratchet wheel to be rotated and this rotation brings into contact with the trip arm 57 on the latch 53 the next pin 67 on the ratchet wheel. The engagement of the pin and the trip arm effects the pivotal movement of the latch 53 until it springs to the open position, illustrated in Figure 6, under the actuation of its over center spring 56. The arm 51 on the cover 6 is then free to move outwardly and the operator can pivot the cover 6 outwardly and slide the bottom thereof from its spring support 8. The dirt container 20 can then be removed and emptied in an obvious manner.

The dirt container being emptied it is replaced within the machine and the cover 6 again positioned. The operator then exerts a downward force upon the latch-operating plunger 55 to force the latch downwardly from the position illustrated in Figure 6 to that illustrated in Figure 1. In the Figure 6 position, it is to be noted, the trip lever 57 has moved to a position rearwardly of the pin 67 which effected the tripping action upon the latch 53 moving to its upper position. When the latch 53 is forced downwardly by the plunger 55 the trip lever is in position to be engaged by the next pin 67. The operator, to return the machine to its normal operating condition, need only rotate the actuating handle 38 from its dotted line position to its full line position, the handle being as close to the casing cover as possible. Thereupon the port-closing valve 81 moves to open position and the machine is again ready for operation.

I claim:

1. In a suction cleaner, suction-creating means, a dirt separator, a dirt receptacle, a casing enclosing said parts and including a removable cover the removal of which gives access to said dirt receptacle, latching means retaining said cover in place on said casing, a program release mechanism positioning said latching means, means to actuate said mechanism to position said latching means to release said cover including a manually operable handle, and means to clean said dirt separator concomitantly with the operation of said mechanism and actuated by said handle.

2. In a suction cleaner, a main casing including a removable cover, a filter in said casing, a latch normally securing said cover on said casing, manually operable means to release said latch, a filter-cleaning nozzle in said casing, means connecting said nozzle to said manually operable means to enable the operator to actuate said nozzle, and program means controlling said latch and adapted to release same under a predetermined schedule of operation of said nozzle.

3. In a suction cleaner, a main casing including a removable cover, a filter in said casing, suction-creating means in said casing to move air through said filter, a latch normally securing said cover to said casing, a filter-cleaning element in said casing movable relative to said filter, program means connecting said element and said latch to release the latter by a predetermined movement of the former, and manually operable means to actuate said element.

4. In a suction cleaner, a main casing including a removable cover and inlet and outlet ports, a filter in said casing, suction-creating means in said casing to move air through said filter, a latch normally securing said cover to said casing, a filter-cleaning nozzle in said casing movable relative to said filter, valve means to connect said filter-cleaning nozzle to said suction-creating

means, valve means to control the flow of air through said inlet port, program means connecting said nozzle and said latch to release the latter upon a predetermined movement of the former, and manually operable means connected to said nozzle and mounted for rotation to actuate said valve means and for displacement to actuate said nozzle.

5. In a suction cleaner, a main casing including a removable cover and inlet and exhaust ports, a dirt container inside said casing displaceable from said casing with said cover removed, an initial dirt separator, suction-creating means in said casing to draw air through said inlet port and through said initial dirt separator, a final dirt separator including a filter to receive air from said suction-creating means, a filter-cleaning nozzle connected to said suction-creating means at said initial separator and mounted for movement relative to said filter, valve means controlling the flow of air through said inlet port and through said nozzle, latch means securing said cover to said casing, a manually operable handle connected to said nozzle and to said valve means, and program means to release said latch upon a predetermined movement of said nozzle by said handle.

6. In a suction cleaner, an elongated main casing including a removable portion, a filter in said casing, securing means normally holding said portion in place, program release means controlling said securing means, a filter-cleaning element movable with respect to said filter, and a handle to actuate simultaneously and with the same movement said program release means and said filter-cleaning element and mounted for translation parallel to the major axis of said casing, characterized in that said handle must be actuated a plurality of times to actuate said program release means to move said release means to their releasing position.

7. In a suction cleaner, a casing including a removable portion, securing means normally holding said portion in place, an initial dirt separator, suction-creating means, and a final dirt separator including a filter arranged in the order given within said casing, a movable nozzle movable on said filter, air-conducting means connecting said nozzle to said initial dirt separator, valve means controlling the flow of air through said nozzle, program release means controlling said securing means, and a single manually operable element to actuate said nozzle, valve means and program release means.

8. In a suction cleaner, a casing, an initial dirt separator, suction-creating means and a final dirt separator in said casing, a nozzle to remove dirt from said final filter, air-conducting means connecting said nozzle to a point of suction in said initial dirt separator, valve means to control the flow of air through said nozzle, and an operating handle mounted for translation and arcuate movement relative to said casing on a single axis and connected to said nozzle and to said valve means, characterized in that the arcuate position of said handle controls said valve means and the translatory movement operates said nozzle.

9. In a suction cleaner, a casing including a removable portion, an initial dirt separator, suction-creating means and a final dirt separator in said casing, a nozzle to remove dirt from said final filter, air-conducting means connecting said nozzle to a point of suction in said initial dirt separator, valve means to control the flow of air

through said nozzle, securing means for said removable portion, program release means controlling said securing means, and an operating handle mounted for translation and arcuate movement relative to said casing on a single axis and operatively connected to said nozzle, to said valve means, and to said program release means

to actuate same, characterized in that the arcuate position of said handle positions said valve means and the translatory movement of said handle actuates said nozzle and said program release means.

CARL O. PENN.
